UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,539, dated September 19, 1899.

Application filed May 29, 1899. Serial No. 718,757. Term of patent 14 years.

To all whom it may concern:

Be it known that I, JEREMIAH A. SCRIVEN, a citizen of the United States, residing in the city, county, and State of New York, have 5 invented and produced a new and original Design for Bifurcated Nether Garments, of which the following is a full, clear, and exact description.

The leading feature of my design is a bifurcated nether garment substantially as shown 10 in the accompanying drawing, the essential feature being the shape of the panel or insert.

In the drawing, A is a bifurcated garment having the tubular members B and in the back thereof a panel or insert C, having the upright edges *d* and the gently-curved outer edges *e*, substantially as shown.

What I claim is—

The design for a bifurcated nether garment, substantially as herein shown and described. 20

JEREMIAH A. SCRIVEN.
